UNITED STATES PATENT OFFICE.

EMILE HARTER, OF PARIS, FRANCE.

RADIATOR FOR EXPLOSION ENGINES.

1,421,221.

Specification of Letters Patent. Patented June 27, 1922.

Application filed December 13, 1919. Serial No. 344,518.

To all whom it may concern:

Be it known that I, EMILE HARTER, a citizen of the Republic of France, and a resident of 4 Square Lamartine, Paris, France, have invented new and useful Improvements in a Radiator for Explosion Engines, of which the following is a specification.

My invention relates to radiators for explosion or internal combustion engines, comprising a turbine or wheel of a centrifugal fan, around which are provided a series of circular tubes concentrically arranged to the axis of the turbine and through which is circulated the cooling water of the motor which may be of a type suitable for use on an automobile.

It has already been proposed, in order to increase the heat-exchanging surface of the apparatus, to provide said tubes with radially laid gills, but these radial gills are obliquely encountered by the air forced by the turbine or centrifugal fan, in such a manner that they obstruct the flow of air and cause eddies to form so that but a very little amount of air passes between the gills.

According to my invention, I obviate this drawback by having the gills so shaped that they receive and guide the air leaving the centrifugal fan turbine, on its course through the said gills.

This construction allows of obtaining a perfect and complete utilization of the heat-exchanging surface of the radiator at all speeds of the motor.

The fan may be provided with a series of annular partitions of different internal diameters, arranged at the entrance of the movable vanes of the turbine, concentrically to the axis of the latter and parallel to its plane of rotation, for the purpose of dividing the air uniformly over the whole area of the vanes and of opposing the sliding of the air towards the disc of the turbine.

In the accompanying drawings—

Fig. 1 is a side elevation, one half in section, of a radiator in which my invention is embodied in one form;

Fig. 2 is a partial front elevation, one half in external view and one half in section on line 2—2 of Fig. 1;

Fig. 3 is a more or less diagrammatic front elevation of the radiator with associated means for controlling its cooling power.

Fig. 4 is a detail view of the gills.

The centrifugal turbine or fan of the radiator consists of curved vanes A, riveted on one side to a flat sheet metal ring B and on the other to a disc C bolted to a hub casting D.

The shaft E, upon which the hub D is keyed, revolves in two bearings F and G containing ball races H; the bearings are protected against dust by felt washers I and at front by a dust cap J.

The bearings F and G are supported by arms K cast with the plates L and M, between which the fan revolves.

The heat-exchanging portion of the radiator is fixed between the plates L and M by 70 the manifolds N and O of the gilled tubes. The manifolds have each for this purpose on one side a screw threaded boss P Q and on the other side a nipple R. S. likewise screw threaded. By means of nuts T and V 75 the whole is held solidly together in correct position, while the tubes and fan are perfectly protected inside the structure.

The upper manifold N allows the expansion of the water which is introduced 80 through the filler W containing a gauze U and accommodating the upper end of an overflow pipe X leading to the bottom of the radiator.

The manifold O, diametrically opposite, 85 has a drain pipe Y.

The gilled tubes Z and a are hard soldered to the manifolds N and O in bosses of a length equal to the diameter of the tube. The heat-exchanging apparatus is therefore, 90 very robust and resists a pressure of 5 kilogrammes per square centimetre.

The gills are bent in accordance with Figure 2 or in any other way, tending to obtain the entrance of air without shocks 95 into the heat-exchanging apparatus, and afterwards a molecular rolling of the air over the surface of the gills.

Moreover the gills upon the tubes Z, which receive the current of cold air, may be of a 100 metal having a higher calorific conductivity than that of the tubes a, which is subjected to air already heated by the tubes Z. The metal is thus fully utilized, and there is no dead weight.

At the intake to the movable vanes of the turbine is arranged a series of annular partitions β , of different internal diameters, concentrically positioned with respect to the axis of the turbine and parallel to its plane 110

of rotation, for the purpose of dividing the air uniformly over the whole area of the vanes and of opposing the sliding of the air towards the disc C of the turbine. The partitions thus constitute a correcting distributor of the air. They are fixed by means of rods, rings and washers to the lugs e, cast integral with the plate L of the fan chamber.

10 The air leaves the apparatus through a perforated metal sheet d supported by the plates L and M.

The circulating water enters the apparatus through the nozzle R of the upper manifold N, passes through the tubes Z and a to the lower manifold O, which it leaves by the nipple S.

The fan is driven by belt upon the pulley e.

15 The constitution of the heat-exchanging surface of the radiator hereabove described, by vanes or gills curved in such a way as to guide the air discharged by the fan, presents the advantage of allowing the easy regulation of the external temperature. It suffices 20 for this purpose to dispose and direct the gills in such a way as to create two air currents symmetrical in relation to an axial plane of the apparatus, which currents are obliged, in order to reach the free air, to 25 traverse exit openings capable of being obstructed to a greater or less extent by a system of adjustable registers. In this way, by closing the registers more or less, according as the external temperature is lower or 30 higher, the temperature of the water cooled by the radiator may be arranged to be always constant. This method presents the additional advantage of allowing the vehicle to be easily and effectively heated.

35 40 When the registers are partly closed, as in the case when the external temperature is low, the hot air leaving the heat-exchanging surface is kept under pressure; this static pressure of the air is utilized to convey it through suitable piping into the body of the vehicle. It is desirable to provide this piping with an air filter to arrest dust and with a register to allow of regulating the supply of hot air.

45 50 A form of construction of a radiator in accordance with the foregoing is represented diagrammatically by way of example in Figure 3, which shows a front view of the radiator with its fan.

55 60 A is the fan or turbine wheel, O and N the manifolds, a the gilled tubes. The gills a¹ on the right are bent in such a way that the hot air at its exit is directed as indicated by the arrow x¹ along the casing d of the radiator which is formed of an unperforated sheet of metal; the gills a² on the left are cambered in the opposite way so that the air is directed as shown by the arrow x². There are thus obtained two gaseous currents which 65 are directed towards the exit orifices d¹ d²

provided with Louvre-registers for example and adapted to be controlled from a distance by the driver of the vehicle.

At one or more points in the radiator there may be arranged hot-air connections r which 70 communicate with the interior of the body-work of the vehicle through a pipe r' provided with an adjusting damper r² and a filter r³ arranged in the heat-nozzle r⁴.

Having now particularly described and 75 ascertained the nature of my said invention and in what manner the same is to be performed I declare what I claim is:—

1. A radiator for explosion engines, comprising a centrifugal fan turbine, tubes concentrically arranged around said turbine, means for circulating cooling water through said tubes, gills on the tubes so shaped that the air leaving the fan turbine is guided without shocks or eddies to its exit passage 80 from the radiator, said gills forming the heat exchanging surface of the radiator, together with a series of annular partitions of different internal diameters, arranged at the intake to the movable vanes of the turbine, 85 concentrically to the axis of the latter and parallel to its plane of rotation, and serving to distribute the air uniformly over the whole area of the vanes and to oppose the sliding of the air towards the disc of the turbine. 90

2. A radiator for explosion engines, comprising a centrifugal fan turbine, tubes concentrically arranged around said turbine, means for circulating cooling water through 100 said tubes, and gills on the tubes so shaped that the air leaving the fan turbine is guided without shocks or eddies to its exit passage from the radiator, said gills forming the heat exchanging surface of the radiator, a 105 closed casing surrounding the gilled tubes, exit openings in said casing, the gills being so shaped as to create currents of hot air directed towards the said openings, and means controlling the said openings. 110

3. A radiator for explosion engines, comprising a centrifugal fan turbine, tubes concentrically arranged around said turbine, means for circulating cooling water through said tubes, and gills on the tubes so shaped 115 that the air leaving the fan turbine is guided without shocks or eddies to its exit passage from the radiator, said gills forming the heat exchanging surface of the radiator, a closed casing surrounding the gilled tubes, 120 exit openings in the bottom of said casing, on either side of the plane of symmetry of the apparatus, means controlling said openings, the gills of the cooling tubes being so directed, on either side of the plane of symmetry of the apparatus, as to create two currents of hot air, symmetrical in relation to said plane and leading to the said adjustable exit openings. 125

4. In a vehicle carrying an explosion en- 130

gine, a radiator for the explosion engine, comprising a centrifugal fan turbine, circular tubes concentrically arranged around said turbine, means for circulating cooling water through said tubes, gills carried by said tubes and so shaped that the air leaving the fan turbine is guided without shocks or eddies to the exit passage from the radiator, said gills forming the heat exchanging surface of the radiator, a casing surrounding

the gilled tubes, and means for leading hot air from the casing to the interior of the vehicle for the purpose of heating the latter.

In testimony whereof I have signed my name to this specification.

EMILE HARTER.
